Attorneys

UNITED STATES PATENT OFFICE

FRANK HUMER, OF DETROIT, MICHIGAN, ASSIGNOR TO GENERAL MOTORS CORPORATION, OF DETROIT, MICHIGAN, A CORPORATION OF DELAWARE

DOOR

Application filed June 28, 1929. Serial No. 374,307.

This invention relates to doors and has particular reference to the doors of automotive vehicles.

Automotive vehicle doors are customarily provided with a window opening at the upper portion and have a window slidably mounted between the door sides. This window has usually been retained at the front by means of integral permanent portions of the door itself and at the rear by means of a removable finish piece. In case it is desired to remove the glass or place a new one in the door, it has always been necessary to remove the rear finishing strip and insert the glass from the rear. In the present invention the usual rearwardly removable finish strip is applied and in addition the front or outer side of the door has secured thereto a removable chromium plated reveal or finish strip to hold the glass in place. This chromium plated finish strip is removable as a unit by loosening the fastening means which secure it to the door.

One of the principal objects of the invention is to provide a removable and readily applicable finish strip or frame portion constructed as a unit and insertable from the outer side of the door. This unit has for its object to add to the finish and appearance of the door and also to retain the window in place at its outer edges.

The door itself is composed of an inverted U-shaped frame to the mid-portion of which there are secured two brackets which support the belt rail. One of the brackets is provided with a lock receiving opening and also extends downwardly alongside the interior of the frame to the bottom of the door to stiffen the structure and form a more rigid frame construction.

Over the door frame the usual panel is applied and flanged to the edge of the frame. The panel is inwardly bent at the window opening and filler strips are preferably applied between the inwardly bent panel portions and the door frame.

The outer window securing frame or reveal is inserted in the window opening over the door panelling from the outer side after the window is in place and is secured in po-

sition by means of screws passing through flanges on three sides of the frame and through tongues bent over the belt rail at the bottom of the reveal.

On the drawings:

Fig. 1 is a side view of an automotive vehicle showing the door of the invention applied thereto.

Fig. 2 is a section on the line 2—2 of Fig. 1.

Figs. 3 and 4 are enlarged detailed views of the structure of Fig. 2.

Fig. 5 is a section on the line 5—5 of Fig. 1.

Fig. 6 is a section on the line 6—6 of Fig. 1.

Fig. 7 is a perspective view of the outer window securing frame or reveal.

Fig. 8 is a perspective view of the inner portion of the door at the lock, showing one of the supporting brackets.

Referring to the drawings the numeral 2 indicates an automotive body as a whole. The body includes the cowl 4, top 6, rear doors 8 and front doors 10. The invention relates particularly to the construction of the doors 8 and 10 and the description which follows will be confined to one door 10, although the construction at the rear doors 8 is the same.

The vehicle preferably has a V-type windshield 12 supported between the central post 14 and the corner posts 16. The corner posts 16 are shaped as shown in Figs. 2 and 3 and are adapted to receive the windshield in the groove 18 and the angle of the door frame at the groove 20.

The center door post is shown at 22 and comprises the two irons 24 and 26 extending from the top to the bottom of the vehicle and secured together at their forward portion by means of the spacer 28 and suitable screws or other fastening elements passed through the irons 24 and 26 and into the spacer 28. A wooden filler is indicated at 30 while fillers 32 and 34 appear at both sides of the inner portion of the door. Finishing strips 36 and 38 which are preferably chromium plated are applied over the filler strips 32 and 34.

The door is hinged as at 40 to the front door post. The hinge leaves 42 and 44 are secured respectively to the post 16 and the frame 46 of the door 10.

The frame 46 is U-shaped and extends from the bottom portion of the door up one side, across the top and down the opposite side. The frame has the right angularly extending flange 48 extending throughout the length of the frame.

Over the frame 46 there is secured the panel 50 which has its edges 54 return bent and flanged over the flange 48 of the frame 46. At its lower portion the panel 50 is also flanged around an iron 52 secured to the bottom wooden frame member 55 of the door.

At its upper portion the door is provided with a window opening 56 adapted to receive 15 the window 58. At the window opening the panel 50 is inwardly flanged as indicated at 60 and filler strips 62 are preferably provided between the flange 60 and the web of the door frame 46. If desired the filler strips may be 20 omitted.

At the rear of the door frame at the window openings, the usual wooden finish strip 66 is provided and is secured to the frame 46 and to the wooden frame member 68 in any 25 suitable way such as by means of screws. This inner finish strip holds the window 58 in place at its inner edges.

At the outer face of the door there is provided the finish strip or reveal indicated as 30 a whole at 70 and shown in perspective in Fig. 7. The reveal 70 is composed of a single piece of chromium plated metal having the flanges 72 and 74 at its sides and the flange 76 at its upper portion. At its lower edge there 35 are provided the tongues 78 which are shown as integral with the reveal but in practice are preferably separate pieces welded to the frame 70. The reveal 70 has the shoulder 80 entirely therearound and against which 40 shoulder the outer edges of the window 58 are adapted to strike or abut in order to hold the window in place. Beyond the shoulder 80 the reveal is suitably curved and terminates at the edge 82 which fits over the face of 45 the panel 50 at the window opening edges.

In practice the reveal 70 is chromium plated and is inserted as a unit from the outer side of the door. This is desirable owing to its integral construction and due to the 50 fact that it is chromium plated it is preferable to show outwardly for appearance purposes. The reveal of course is inserted in the door frame after the window 58 is in place and after the window is dropped in the channel 55 84 its lowermost position, screws 86 are applied through the flanges 72, 74 and 76 into the filler strips 62, or filler strip and frame 46, to rigidly hold the reveal in place. At the bottom of the frame the tongues 78 are inwardly bent as shown in Fig. 6 and screws 60 are passed through the tongues and into the belt rail 88. This particular construction of the reveal or outer securing frame is one of the essential parts of the invention. It greatly 65 enhances the appearance of the door and

renders the window removable from the outer as well as the inner side. It also eliminates any welding operation and equips the door with an outer removable frame member instead of the usual integral window supporting member of the door.

At the non-hinged or lock side the door is provided with the bracket 90 secured to the frame 46 and to the panel 50 by welding as indicated at 92. The bracket has the upper shoulder portion 94 which is adapted to receive a belt rail 88. Suitable screws 96 are passed through the bracket 90 to secure the belt rail in position.

The bracket 90 has the downwardly extending leg portion 98 secured to the door frame. The leg 98 extends to the bottom of the door and is for the purpose of strengthening the door and obtaining a more rigid construction at its non-hinged side. The bracket 90 is provided with a suitable opening 100 to receive the door lock and a second opening 102 for the reception of the shank of the door handle.

The hinge side of the door has a bracket 98 which corresponds and is similar to the bracket 90 shown in Fig. 8 except that it does not have the downwardly extending portion 98 containing the openings 100 and 102 but is merely shaped to form the shoulder 94 to 95 retain the belt rail.

The window 58 is provided with the usual felt channel run or guide 104 and the bottom metallic support 106 which serves as an attachment for the window regulator to raise and lower the window.

A suitable fabric 108 shown in Fig. 3 is secured between the finish strip 66 and the door and projects away from the door to form a tight joint when the door is in closed position.

I claim:

1. In a vehicle door having a window opening, means at the inner door side to support a window at its inner edge, means insertible in the door as a unit from the outer side and secured to the door to support said window at its outer edges, flanges at three of the sides of said laterally insertible means, a plurality of tongues at the fourth side, and means passing through said flanges and tongues to secure said means to said door.

2. In a vehicle door having a window opening, a frame, a door panel flanged around and secured to said frame, a finishing strip on the inner side of the door supporting a window at its inner edges, and a removable unitary finishing frame on the outer side of the door insertible as a unit in the door from its outer side and extending over the panel edge at the door and supporting said window at its outer edges.

3. In a vehicle door having a window opening, a frame, a door panel flanged around and secured to said frame, means on

the inner side of the door to retain a window, a removable unitary finishing frame on the outer door side insertible as a unit in the door from its outer side and extending over the panel edge at the window opening, and flanges on the finishing frame by means of which it is secured to the door.

4. In a vehicle door having a window opening, a frame, a door panel flanged around and secured to said frame, means on the inner side of the door to retain a window, a removable unitary finishing frame on the outer door side insertible as a unit in the door from its outer side and extending over the panel edge at the window opening, and flanges on the finishing frame by means of which it is secured to the door.

5. In a vehicle door having a window opening, a frame, a door panel flanged around and secured to said frame, means on the inner side of the door to retain a window, a removable unitary finishing frame on the outer door side insertible as a unit in the door from its outer side and extending over the panel edge at the window opening, and flanges on the upper and lateral sides of the frame and tongues on the lower side by means of which said finishing frame is secured to the door.

30 6. In a vehicle door having a window opening, a frame, a panel flanged around and secured to said frame, a filler between the door frame and panel at the window opening, means on the inner side of the door to retain a window, a removable unitary finishing frame on the outer door side insertible as a unit in the door from its outer side and extending over the panel edge at the window opening, flanges on the finishing frame, and means 35 passing through flanges and panel and into said filler to secure said finishing frame to said door.

7. In a vehicle door having a window opening, a frame, a panel secured to said frame, a belt rail at the lower end of said opening, means on the inner side of the door to retain a window, a removable unitary finishing frame on the outer door side, insertible as a unit in the door from its outer side and extending over the panel edge at the window opening, tongues on said finish strip bent over said rail, and means passing through said tongues and into said rail to secure said finishing frame to said door.

55 8. In a vehicle door having a window opening, a frame, a panel secured to said frame, a belt rail at the lower end of said opening, means on the inner side of the door to retain a window, a removable unitary finishing frame on the outer door side insertible as a unit in the door from its outer side and extending over the panel edge at the window opening, flanges on some of the sides of the finishing frame, tongues on the lower edge 60 of the finishing frame, means passing through

said flanges and tongues and into said door and belt rail to secure said finishing frame to the door.

9. In a vehicle door having a window opening, a frame, a panel flanged around and secured to said frame, a filler between the door frame and panel at the window opening, a belt rail at the lower end of said opening, means on the inner side of the door to retain a window, a removable unitary finishing frame on the outer door side insertible as a unit in the door from its outer side and extending over the panel edge at the window opening, flanges on the finishing frame, means passing through flanges and 70 panel and into said filler to secure said finishing frame to said door, tongues on said finish strip bent over said rail and means passing through said tongues and into said rail to secure said finishing frame to said door.

10. In a vehicle door having a window opening, a frame around the outside of the door, a panel over the frame, brackets secured to the frame and panel inside the door, 75 one of said brackets provided with an opening for receiving the door lock, and a belt rail supported in said brackets.

11. In a vehicle door having a window opening, a frame around the outside of the door, a panel over the frame, brackets secured to the frame, one of said brackets extending from the belt rail to the bottom of the door and provided with an opening for receiving the door lock, and panel inside the door and 80 a belt rail supported in said brackets.

12. In a vehicle door having a window opening, a window in said opening, means at the inner door side to support the window at its inner margin, a panel over the outer portion of the door, said panel having a window opening at its upper portion, and means laterally insertible in the opening in the door panel as a unit from the outer side only and secured to the door at the outside to support 85 said window at its outer margin.

13. In a vehicle door having a frame and a window opening, a window in said opening, a frame member on the inner door side to support the window at its margin, a panel over the outer portion of the door, said panel having a window opening at its upper portion, a second frame member at the outer side of the door insertible as a unit from the outside 90 only in the opening in said door panel to hold the opposite side of said window at its margin, and means on said second frame member to secure it to the outside of the door frame.

14. In a vehicle door having a frame and a window opening, a window in said opening, a frame member on the inner door side to support the window at its margin, a panel over the outer portion of the door, said panel having a window opening at its upper portion, a second frame member at the outer side of 95

the door insertible as a unit from the outside only in the opening in said door panel to hold the opposite side of said window at its margin, and a plurality of tongues at one edge of said frame to secure it to the outside of the door.

15. In a vehicle door having a frame and a window opening, a window in said opening, a frame member on the inner door side to support the window at its margin, a panel over the outer portion of the door, said panel having a window opening at its upper portion, a second frame member at the outer side of the door insertible as a unit from the outside only in the opening in said door panel to hold the opposite side of said window at its margin, and means on said second frame member to secure it to the outside of the door frame, said means comprising a plurality of tongues at the edge of the frame bent onto the door after said second frame is in position.

16. In a vehicle door having a window opening, a window in said opening, means at the inner door side to support the window at its inner margin, a panel over the outer portion of the door, said panel having a window opening at its upper portion, means insertible in the opening in the door panel as a unit from the outer side only and secured to the door at the outside to support said window at its outer margin, a flange and a plurality of tongues at the edge of said laterally insertible means, and means passing through said flange and tongues to secure said means to said door.

In testimony whereof I affix my signature.
FRANK HUMER.
